PER ARVID PETERSON, OF TRENTON, NEW JERSEY, ASSIGNOR TO DE LAVAL STEAM TURBINE COMPANY, OF TRENTON, NEW JERSEY, A CORPORATION OF NEW JERSEY.

BALANCING OF CENTRIFUGAL PUMPS.

1,151,964.

Specification of Letters Patent. Patented Aug. 31, 1915.

Application filed August 12, 1913. Serial No. 784,432.

To all whom it may concern:

Be it known that I, PER ARVID PETERSON, a subject of the King of Sweden, and a resident of Trenton, in the county of Mercer and 5 State of New Jersey, have invented certain new and useful Improvements in Balancing of Centrifugal Pumps, of which the following is a specification.

My invention relates to means for the automatic balancing of centrifugal pumps against end thrust and comprises means whereby centrifugal pumps, either of the one stage or of the multistage type, are balanced against end thrust at all times, 15 making the provision of thrust bearing unnecessary.

The objects of my invention are to maintain the impellers of centrifugal pumps in perfect balance at all times, to avoid the use of thrust bearings, to reduce wear and leakage in such pumps to a minimum, and to simplify the construction of such pumps.

I will now proceed to describe my invention with reference to the accompanying drawings, and will then point out the novel features in claims.

In the drawings: Figure 1 shows a fragmentary axial section of a single stage centrifugal pump embodying my invention, and 30 Fig. 2 shows a similar section of a multistage centrifugal pump embodying my invention.

Referring first to Fig. 1, 1 designates the casing of a centrifugal pump, 2 the impeller shaft of such pump, 3 an impeller mounted on such shaft, 4 the usual admission duct and 5 the usual discharge chamber. The impeller is provided with the usual passages 6, receiving liquid from the admission duct 4 and discharging into the space 7 and thence into the discharge duct 5. In rear of the impeller there is, as customary, a balancing chamber 8. On the inlet side of the impeller I have indicated the usual labyrinthine packing comprising a stationary labyrinthine ring 9 and a rotating labyrinthine ring 10, the latter mounted upon the impeller and rotating with it; the two rings, 9 and 10, having intermeshing flanges providing a labyrinthine passage in the usual 45 manner. At the rear of the impeller I have indicated other labyrinthine rings, 11 and 12, ring 11 being stationary and ring 12 being mounted upon and rotating with the impeller; these rings 11 and 12 likewise having 55 intermeshing flanges providing a labyrinthine passage; but the rings 11 and 12 face in directions opposite that which has been the practice heretofore in centrifugal pumps; for according to former practice it 60 has been common for the stationary impeller ring on the rear side of the impeller to have its flanges facing toward the impeller; and correspondingly, according to former practice, the rotating labyrinthine ring on the 65 rear side of the impeller has had its flanges facing from the impeller; whereas just the reverse is true of the construction herein illustrated and described. The impeller shaft is allowed slight play for longitudinal 70 motion; which movement will reduce or increase, as the case may be, the distance between the ends of the flanges 13 of ring 12 and the ends of the corresponding grooves of ring 11, and will correspondingly decrease or increase, as the case may be, the distance between the ends of the flanges 14 of the stationary ring 11, and the ends of the corresponding grooves in ring 12. Of course as the distance between the ends of 75 flanges 13 and 14 and the ends of the corresponding grooves increase, the distance between the flanges 15 of the ring 10 and the ends of the grooves of the ring 9, will increase, and vice versa. In the operation of 80 this pump, since the pressure at 7 is necessarily greater than the pressure at 4, while the pump is in operation, there is a tendency for leakage from space 7 between rings 9 and 10 back into the inlet 4 and a 85 corresponding tendency for leakage from space 7 between rings 11 and 12 back into balancing chamber 8; and this latter leakage, if no vent were provided from chamber 8, would lead to a pressure in chamber 8 90 equal to that in space 7; therefore I provide a duct 16 connecting the balancing chamber 8 with the inlet portion of the passages 6 of the impeller.

It will be seen that in the construction 100

shown if there be an excess of thrust toward the right the impeller will move slightly to the right, increasing the distance between the flanges of rings 12 and 11 and the ends of the grooves in which those flanges are located, and so permitting increased flow between the rings 12 and 11, with resulting building up of pressure in balancing chamber 8 sufficient to restore 10 equality of thrust in both directions; conversely, if the thrust toward the left be greater than the thrust toward the right, the impeller will move slightly to the left, decreasing the distance between the ends of 15 the flanges of the rings 11 and 12, and the ends of the grooves in which those rings are located, with resulting decrease of flow between rings 11 and 12, and therefore resulting decrease of pressure in balancing 20 chamber 8.

Heretofore, in centrifugal pumps provided with labyrinthine packing, it has been customary to provide radial clearance between the flanges of the stationary and the 25 rotary labyrinthine rings of the grooves in which such flanges are located; such clearance amounting in some cases to as much as one-sixty-fourth of an inch. Such clearance has necessarily resulted in considerable 30 leakage into the balancing chamber and into the inlet duct of the pump. It has also been common to employ a balancing duct, similar to duct 16, connecting the balancing chamber in rear of the impeller with the inlet 35 portion of the impeller; and since the area of cross section of the balancing duct or ducts 16 must be proportionate to the leakage between the labyrinthine packing rings, and since these labyrinthine rings are necessarily 40 subjected to wear with consequent increase of leakage (in the former constructions wherein radial clearance between the rings has been provided), it has been necessary at frequent intervals, as the radial 45 clearance between the labyrinthine packing rings increases from wear, to renew these rings as otherwise the thrust may increase to a dangerous extent and also decrease the capacity and efficiency of the pump to a 50 material extent. According to my invention I reduce the radial clearance between the intermeshing labyrinthine rings to the lowest amount consistent with good running, and reasonable ease of fit, and instead 55 provide end clearance between the ends of the flanges of the labyrinthine rings, and the ends of the grooves in which such rings are located; which end clearance varies according to the position assumed by the impeller at any instant. Since, according to my invention, the throttling action in the labyrinthine rings by means of which the automatic balancing of the pump is effected, occurs mainly between the ends of

the flanges of the labyrinthine rings and the 65 ends of the grooves in which such flanges run, wear of these flanges has very little effect on the leakage between these rings, since the impeller automatically assumes a position whereby the leakage is regulated to 70 give the required pressure in balancing chamber 8, and therefore in practice renewal of the labyrinthine packing rings is 75 very seldom required. It also follows, from my invention, that the smaller be the area 80 of cross section of the balancing duct or ducts 16, the smaller is the leakage which can be taken care of by these ducts and consequently a smaller axial clearance will be 85 established automatically between the ends 90 of the flanges of rings 12 and 11 and the ends of the grooves in which such flanges run. Of course, there is a minimum permissible clearance between the ends of these flanges and the ends of the grooves in which 95 they run, which minimum clearance may vary under different conditions of use; and the area of the balancing duct or ducts 16 should be proportioned in the design of the pump, to give that minimum axial clearance 100 of the flanges of the labyrinthine rings 11 and 12 which the conditions of use require.

In Fig. 2 I have illustrated my invention as applied to a two stage centrifugal pump. It will be obvious that the number of stages 95 of such pump might be greater than shown. The construction is in general the same as in Fig. 1 except that labyrinthine packing rings 17 and 18 are provided between the stages of the pump to reduce to a minimum 100 back flow between stages, these rings being so arranged that they control the extent of leakage in the same manner as rings 11 and 12.

In a companion application, filed August 105 12, 1913, Sr. No. 784,433, I have illustrated a centrifugal pump which in construction and method of automatic balancing is the same as that herein illustrated and described, except that instead of employing a balancing 110 duct or ducts (such as 16 herein) in the impeller, connecting the balancing chamber in rear of the impeller, with the admission portion of the impeller, I have provided a balancing duct, extending from the balancing 115 chamber in rear of the impeller, to the admission duct of the casing, and except that in the multistage pump shown in my said companion application labyrinthine packing between the stages is not provided, and in 120 such multistage pump of my companion application, the balancing duct extends from the balancing chamber in rear of the last impeller to the admission duct of the casing in front of the first impeller; whereas in the 125 structure of my present application, a balancing duct 16 is provided in each impeller. The construction of this present case is pref-

erable, in multistage pumps, designed for very high pressures, and the construction in multistage pumps of my said application filed August 12, 1913, Sr. No. 784,433, 5 is preferable for moderate pressures.

I am aware that the automatic balancing as to end thrust of the impellers of single stage and multistage pumps has been proposed heretofore; but so far as I know, this 10 application, and my said companion application, filed August 12, 1913, Sr. No. 784,433, are the first instances of automatic balancing obtained by throttling action between the 15 ends of flanges of labyrinthine packing rings and the ends of grooves, in which such flanges work, regulated by automatic axial motion of the impeller.

The claims generic to the structure shown in this present application, and in my said 20 companion application filed August 12, 1913, Sr. No. 784,433, will be found in the said companion application.

It will be noted that in the constructions shown in this application, the impeller labyrinthine packing ring or rings 12 on the rear side or sides of the impeller or impellers is or are of the same diameter as the ring or rings 10 on the inlet side of the impeller or impellers. In my said companion 25 application filed August 12, 1913, Sr. No. 784,433, I illustrate a construction involving the use of automatically adjusted throttling means for regulating flow of liquid out of the balancing chamber 8; and the use of such 30 automatically adjusted throttling means permits the impeller labyrinthine packing ring or rings on the rear side or sides of the impeller or impellers to be made of larger diameter than the impeller labyrinthine packing ring 35 or rings on the inlet side of the impeller or impellers, which is often advantageous. In the construction shown herein, since no such 40 throttling means is employed, the suction pressure of each impeller should exist in the balancing chamber 8 of that impeller, in order that the impeller may operate in balance; and in the construction shown herein, such will be the case, under any operating 45 conditions as to head or capacity.

50 What I claim is:

1. A centrifugal pump comprising in combination a casing having a flow passage within it and an impeller within said casing mounted for slight axial motion therein 55 as well as for rotary motion, and having a balancing chamber on the rear side of such impeller and between the impeller and the casing, said impeller provided with a balancing duct connecting such balancing 60 chamber with the inlet side of the impeller, of means for controlling leakage from the flow passage of such casing to said balancing chamber comprising labyrinthine packing rings, one carried by the casing and the

other by the impeller, and one provided 65 with a cylindrical flange and the other with a corresponding cylindrical groove adapted to receive such flange, there being end clearance between the end of such flange and the base of such groove, the working face of the 70 impeller labyrinthine ring facing that impeller, whereby axial movement of the impeller due to unbalanced thrust tends to restore balance of thrust by increase or decrease, as the case may be, of the flow between such labyrinthine rings. 75

2. A multistage centrifugal pump comprising a casing having a flow passage through it divided into stages, and an inlet duct and outlet duct communicating with such flow passage, a multistage impeller structure within said casing comprising separate impellers for the several stages, there being a balancing chamber in rear of each impeller and means for the escape of liquid 80 from each such balancing chamber, of means for controlling leakage from the flow passage of such casing to said balancing chambers comprising labyrinthine packing rings between each such balancing chamber 85 and the flow passage, each such labyrinthine packing comprising two coacting labyrinthine rings, one carried by the casing and the other by the impeller, and one provided with a cylindrical flange and the other with 90 a corresponding cylindrical groove adapted to receive such flange, there being end clearance between the end of such flange and the base of such groove, that side of each such impeller labyrinthine ring which coacts with 95 the casing labyrinthine ring facing toward the impeller, whereby axial movement of the impeller structure, due to unbalanced thrust tends to restore balance of thrust by increase or decrease, as the case may be, of flow between such labyrinthine rings. 100

3. A multistage centrifugal pump comprising a casing having a flow passage through it divided into stages, and an inlet duct and outlet duct communicating with such flow passage, a multistage impeller structure within said casing comprising separate impellers for the several stages, there being a balancing chamber in rear of each impeller and means for the escape of liquid 110 from each such balancing chamber, of means for controlling leakage from the flow passage of such casing to said balancing chambers comprising labyrinthine packing rings between each such balancing chamber and 115 the flow passage, each such labyrinthine packing comprising two coacting labyrinthine rings, one carried by the casing and the other by the impeller, and one provided with a cylindrical flange and the other with 120 a corresponding cylindrical groove adapted to receive such flange, there being end clearance between the end of such flange and the 125

base of such groove, that side of each such impeller labyrinthine ring which coacts with the casing labyrinthine ring facing toward the impeller, and other labyrinthine packing 5 between the balancing chamber of one stage and the stage in advance.

In testimony whereof I have signed this

specification in the presence of two subscribing witnesses.
